F. P. HILDEBRANDT,
PAPER ROLLING MACHINE,
APPLICATION FILED DEC. 18, 1916.

1,403,246.

Patented Jan. 10, 1922.

UNITED STATES PATENT OFFICE.

FRANK P. HILDEBRANDT, OF SAUGERTIES, NEW YORK.

PAPER-ROLLING MACHINE.

1,403,246.

Specification of Letters Patent. Patented Jan. 10, 1922.

Application filed December 18, 1916. Serial No. 127,616.

To all whom it may concern:

Be it known that I, FRANK P. HILDEBRANDT, a citizen of the United States, and a resident of Saugerties, county of Ulster, 5 State of New York, have invented certain new and useful Improvements in Paper-Rolling Machines, of which the following is a specification.

My invention relates to improvements in 10 paper rolling machines, the main object of the invention being to provide a machine of this class which is simple and efficient in operation and construction, and to this end, the invention comprises various combinations of features, as more particularly set 15 out in the appended claims. The machine may be used for rolling paper napkins, paper towels, &c., particularly crepe paper. The accompanying sheet of drawings illustrates 20 a machine embodying the improvements in one form.

In the drawings Fig. 1 is an elevation of the machine. Fig. 2 is a plan view of the same, certain parts being broken away to 25 more clearly illustrate others. Fig. 3 is a perspective view of the rotary cutting knife. Fig. 4 is a detail, illustrating parts which directly roll the paper. Fig. 5 illustrates the roll of paper as it comes from the machine. Fig. 6 illustrates the paper roll after 30 it is folded by hand, and Fig. 7 is a section taken on the line 7—7 of Fig. 2.

Referring to the drawings, 1 represents the supply roll of paper which is rolled 35 upwardly and over a cross-bar 2 by means of rollers 3 and 4. The paper is then fed downwardly and upwardly, to form a loop, and then passes over a cross-bar 5, from which it is fed by means of rollers 15 and 40 16 downwardly over a plate 6 and cutting edge 7, which cutting edge cooperates with the rotary knife 8 to cut the strip of paper into suitable lengths. The cut-off piece of paper is then conveyed by substantially 45 horizontal belts 9 on which it drops until it meets the upright belts 10, which forces the paper upwardly until it meets the obstructing fingers 11, so that the paper is caused to be formed into a roll, as indicated 50 in Figs. 1 and 4. The roll of paper is then taken from the machine by hand and the operator then flattens it down, as shown in Fig. 5, and folds it once or twice and pastes a band around it, so that the final product 55 takes the form shown in Fig. 6.

The roller 3 is mounted in the side frames 13 of the machine, while the roller 4 simply lies loose on the inclined faces 12. 14—14 represent pins which guide the paper over the plate 5 to the feeding rollers 15 and 16. 60 The plate 6 is provided with fingers 17, which rest in circular grooves 18 in the roller 16, so that the paper is stripped from the roller 16 and caused to be fed downwardly over the plate 6. The cutting edge 65 or member 7 is fastened to a cross-bar 19, which is adjustable by means of adjusting screws 20. The rotary cutting knife 8 is carried by means of a rotary shaft 22, which on one end carries a pulley 21, partly surrounded by belt 23, carrying on one end a weight 24 and the other end of which is fastened to the table 25 which is fastened to the top of the frame of the machine. This belt 23 therefore forms a friction retard- 70 ing means, which takes up any slack in the mechanism which drives the rotary cutting knife, so that it always cuts the paper into pieces of the same length. 75

The power for driving the apparatus is 80 derived from the belt 26, which drives the pulley 27 on the shaft 28. Shaft 28 carries a sprocket wheel 29, which transmits power to sprocket wheel 30 by means of a sprocket chain, sprocket wheel 30 being 85 secured to the shaft 22, which carries the rotary cutting knife 8. Shaft 28 also carries a sprocket wheel 31, which, by means of a sprocket chain, transmits motion to a sprocket wheel 32 on a shaft 33, which shaft 90 carries pulleys 34 and 39. Pulley 34 transmits motion to the feed roller 3 by means of a belt passing over a pulley 36 secured to the feed roller 3. The shaft of the feed roller 3 also carries a cone shaped pulley 37, 95 which, by means of a belt 50 drives a cone shaped pulley 38 fixed on the shaft of the feed roller 16. The position of the belt 50 on the cone pulleys 37 and 38 is adjusted by means of a belt shifter 51 (see Fig. 7), 100 adapted to slide laterally on a rod 52 secured to the frame of the machine. The belt shifter 51 is adjusted laterally by means of the adjusting screw 53, which is provided with a hand wheel 54. By this arrangement the relative speed of the feeding rolls 3, 4, and feeding rolls 15, 16 is adjusted so as to maintain the loop of paper therebetween of the desired length. When operating 105 on crepe paper, it is found that without 110

such adjustment, the loop of paper is either likely to become too long or to be taken up altogether, causing the paper to be unduly stretched or torn. Especially is this so with 5 different crepe papers, some of which have more crepe or stretch in them than others.

10 Pulley 39 on shaft 33 drives a pulley 40 on shaft 41, which carries a roller 42, over which pass the belts 9, the other end of the belts passing around the roller 43. Intermediate the rollers 42, 43, the belts 9 pass between idle rollers 47 and 48, mounted in grooves 49 in the side frame of the machine. The set of belts 10, which are substantially 15 at right angles to belts 9, pass over the roller 43 and also the roller 44, being driven by the roller 43, which is, in turn, driven by the belts 9.

As the paper is fed downwardly over the 20 plate 6, it drops upon the conveyor belts 9, and at the proper time is cut off by the rotary cutting knife 8. The cut-off strip then approaches the belts 10, which cause the same to turn upwardly, and the roll formation started. The fingers 11 positively 25 direct the paper backwardly, so as to complete the rolling of the paper in a satisfactory manner.

It will be clear that many changes and 30 modifications may be made without departing from the spirit and scope of the invention in its broader aspects, and hence it is desired to cover all arrangements coming within the language of the appended claims.

35 While certain features of the construction disclosed herein for the purpose of making clear my invention have not been claimed, the right to claim such features, particularly the feeding mechanism, is specifically 40 reserved.

What I claim as new and desire to secure by Letters Patent is:

1. In a device of the class described, means 45 for coiling sheet material comprising a tight conveying belt for receiving lengths of sheet material to be coiled, a second tight belt at an angle to said first named belt and positioned adjacent thereto and in line with the portion thereof receiving the material, said 50 belts running in the same direction and means for turning the material backward upon itself.

2. In a device of the class described, means 55 for coiling sheet material comprising a tight conveying belt for receiving lengths of sheet material to be coiled, and a second tight belt at an angle to said first named belt and positioned adjacent thereto and in line with the portion thereof receiving the material, 60 said belts running in the same direction.

3. In a device of the class described, means 65 for coiling sheet material comprising a tight conveying belt, and means for turning the

material back upon itself as it lies upon said belt to form a detached roll. 65

4. In a device of the class described, means for coiling crepe paper comprising means including a belt for conveying a flat web and supporting a coil of the paper and means for turning the paper conveyed by 70 said belt back upon itself to form a detached roll thereof.

5. In a device of the class described, means for coiling severed lengths of crepe paper, comprising a plurality of belts, one of said 75 belts being arranged to move the paper into contact with another of said belts to turn the end thereof, and means for turning said end backward upon the length of paper.

6. In a device of the class described, means for coiling severed lengths of crepe paper, comprising rollers, and a plurality of belts running over said rollers, the rollers over 80 which any belt runs being relatively fixed and said belts being arranged at an angle to one another.

7. In a device of the class described, means for coiling severed lengths of crepe paper, comprising a plurality of tight belts arranged at an angle to one another and to 90 run in the same direction, and means for directing the paper backwardly to form it into a detached roll.

8. In a device of the class described, means for coiling severed lengths of crepe paper 95 comprising a plurality of tight belts arranged at an angle to one another and to run in the same direction about their centers of support.

9. In a device of the class described, means 100 for coiling severed lengths of crepe paper comprising a plurality of tight belts arranged at an angle to one another, one of said belts being substantially horizontally positioned and another of said belts extending upwardly therefrom at an angle thereto. 105

10. In a device of the class described, means for coiling severed lengths of crepe paper, comprising a plurality of tight belts arranged at an angle to one another, said 110 belts being positioned to support the paper against the action of gravity.

11. In a device of the class described, means for coiling severed lengths of crepe paper, comprising a plurality of tight belts 115 arranged at an angle to one another.

12. In a device of the class described, means for coiling severed lengths of crepe paper, comprising a plurality of sets of straight belts, the sets being so related that 120 the direction of motion of one set is at an angle to the direction of motion of the other set.

In testimony whereof, I have signed my name to this specification.

FRANK P. HILDEBRANDT.
